DATA PROCESSOR HOUSING

Richard S. Massarella, Philadelphia, Pa., assignor to
Sperry Rand Corporation, New York, N.Y., a corpora-
tion of Delaware

Filed May 10, 1961, Ser. No. 65,104

Term of patent 7 years

(Cl. D26—5)

FIG. 1

Des. 197,465

PAGE 2

FIG. 2

FIG. 3

FIG. 1 is a left side front perspective view of the data processor housing, showing the new design;

FIG. 2 is a right side rear perspective view of the data processor housing; and

FIG. 3 is a top view of the data processor housing.

The characteristic features of the new design include, when viewed from the front or rear, a combination of plurality of groups of four vertical panels wherein three adjacent panels in each group are substantially flush with one another while the fourth panel in each group is recessed away from the other three panels, combined with a horizontal row composed of sets of grill plates, one set being disposed below each set of two panels along the front and rear; and further includes side panels at the left and right which protrude the front and rear of the housing.

I claim:

The ornamental design for a data processor housing, as shown and described.
